Application March 2, 1932, Serial No. 596,254
 In Great Britain March 4, 1931

3 Claims. (Cl. 178—69.5)

This invention relates to systems for the electrical transmission of views, scenes, objects, or optical images of the same to a distance, by means of wires, or by radio transmission; and 5 more particularly to television or like systems by which two or more persons situated at a distance from each other are enabled to see and hear each other simultaneously or selectively.

In two- or multi-way television systems, it is 10 desirable that simultaneous transmission and reception of images of a plurality of objects at the several co-operating stations should take place within the period of the retentivity of vision of each observer.

15 It has formerly been proposed to accomplish two-way television in which this desirable feature is obtained, in several ways.

For instance, in the specification of British Letters Patent No. 309,965, there is described 20 apparatus for effecting television between two stations, comprising at each station a transmitting device and a receiving device, which devices are mechanically connected together and driven by a single motor.

25 In one embodiment of this apparatus, a disc at each station is provided with two concentric spirals of apertures, lenses, or the like, to serve respectively for transmission and reception.

Further, in such a system, synchronism is 30 judged by the movement or appearance of the image on the receiving screen at either station, and isochronization and phasing of the mechanism at the two stations may be effected at either station, or at both.

35 The chief disadvantages of the system disclosed in the specification of British Letters Patent No. 309,965 are that, in order to effect simultaneous transmission in two directions, either two channels of communication must be 40 employed, or else two effective channels must be provided by superposing one or both of the television signals upon an appropriate carrier frequency, according to practice known in the art, and that, when the observer at each station 45 is looking at the received image of the observer at the other station, he is viewed by the scanning device at his own station rather obliquely, and a full-face representation of him is not transmitted.

50 In my co-pending application for British Letters Patent No. 34064/30, I have described certain methods of, and apparatus for, transmitting a full-face representation of the observer at each station, while he is looking directly at the reconstituted image of the observer

at the other station, which methods consist essentially in the provision of means for reconstituting an image at each station within the solid angle of the scope of the scan at that station, and in irradiating the observer at each station with invisible rays for the purpose of effecting traversal by the scanning device, in order that the observer may be able to view the reconstituted image, without being dazzled.

In previously devised systems, it has also been 65 necessary to use two or more channels of communication between an operator-observer at one station and the corresponding operator-observer at the second station, in the case of two-way 70 television transmission and reception (see, for instance, the specification of British Letters Patent No. 309,965). This necessity constitutes a serious detraction from the commercial value of such a system when long distances are to be covered by transmission through telephone land- 75 lines or submarine cables, for the electrical frequency-attenuation correctors and loading coils, repeaters and the like, associated with each such transmission circuit, are expensive in initial cost and upkeep. When, on the other hand, com- 80 munication is effected by means of radio-transmitting and receiving apparatus, duplication of the apparatus at the transmitting and receiving stations is almost unavoidable, and two discrete wavelengths must be employed, one for 85 the incoming and one for the outgoing television transmission, with, possibly an additional wavelength, or alternative channel of communication, for speech.

According to the present invention, it is proposed to employ only one channel of communication between the stations of a two-way or multiple-way television system, and to transmit intelligence from each station discontinuously, the quiescent periods during which one of the 95 stations is not transmitting intelligence being employed for the reception of intelligence from the other stations of a group of co-operating stations of a multiple-way system and this form of transmission is utilized to provide an im- 100 proved means, as hereinafter described, for obtaining synchronism between two stations, or between some or all of a group of co-operating stations.

According to another feature of this invention, we propose to transmit the image signals from each of two co-operating stations directly out of phase, that is to say a high light at one station will result in an impulsive flow of current in a given direction in the communicating 110

channel and a high light at the other station will result in an impulsive flow, not in the opposite direction, but in the same direction; by this method of transmitting we can obtain 5 very efficient synchronizing.

In order that the present invention may be more clearly described and ascertained, reference is made to the accompanying diagrammatic drawings in which:

10 Figure 1 shows a complete two-way television system.

Figure 2 shows the form of scanning disc used in the system.

15 Figures 3 and 4 show the relative positions of the discs at the two stations.

Figure 5 illustrates the method of applying the image signals to the transmission line to obtain efficient synchronizing.

20 Figure 6 shows a circuit, the use of which prevents the local image from affecting the local light-relay.

25 Figure 1 illustrates, by way of example, a two-way television system incorporating a method of maintaining synchronism between co-operating scanning devices at the two stations in accordance with the present invention. In this system each station is provided with a rotary scanning device for the purpose of effecting traversal of an operator thereat and at the same time reconstituting an image for his benefit, according to practice well-known in the art per se.

30 The nature of the various elements at one of the co-operating stations, to which those at the other exactly correspond, will now be described 35 and their various functions explained.

At the station on the left hand side of Figure 1, element 2 is a scanning disc mounted upon the shaft of a driving motor 28 and provided with a double series of apertures, each series 40 conforming to a single convolution of a spiral to effect traversal according to practice very well known in the art, but the apertures of one series lying upon radii of the disc mid-way-between the radii upon which the apertures of the other 45 series lie. Moreover, the radius of the outermost aperture of one series, hereinafter referred to as the "inner series" is substantially less than the radius of the innermost aperture of the other series hereinafter referred to as the "outer 50 series."

The disc 2 is also shown, in greater detail, in Figure 2.

55 A light source, preferably comprising an electric arc, 4, is provided, and co-operates with a condensing lens, 6, to illuminate with substantially even intensity an area of the disc 2 through which area pass the apertures of the inner series in ordered sequence during the rotation of the disc. Upon the opposite side of 60 the disc 2 from the arc 4 there is a projecting lens 10 which serves to focus an image of each of the apertures of the inner series in turn upon an operator 8 during the passage of the said aperture across the field on the disc illuminated 65 by the arc 4 in co-operation with the lens 6.

70 Co-operating with the outer series of apertures in the disc 2 there is an element 20 comprising a glow discharge lamp of type well-known in the art having a flat rectangular cathode substantially co-extensive in one sense with the pitch of the spiral to which the apertures of the outer series conform, and in the other with the width, in the direction of motion of the disc 2, of an image to be reconstituted thereby. Upon the 75 opposite side of the disc 2 from the glow dis-

charge lamp 20 there is a magnifying lens 22, which serves to present to the operator 8, an enlarged erect virtual image of an area of the disc 2 immediately in front of the glow discharge lamp 20.

80 The glow discharge lamp consists preferably of a neon-filled tube in which the cathode glow is excited at current densities of and above about 5 milliamperes over substantially the whole of at least one surface of the rectangular cathode.

85 A mask or shield 29 serves appropriately to "frame" those portions of the inner and outer series of apertures which are to be operative in scanning and reconstituting respectively.

90 A photoelectric cell or a group or series of groups of photoelectric cells represented diagrammatically at 12 in Figure 1 is or are adapted directly to receive upon its or their light sensitive surface or surfaces a part of the light (which term is herein used to indicate electromagnetic radiation of wavelength either shorter than, comprising, or larger than those wavelengths to which the human retina is sensitive) diffused from the surface of the operator or other object being scanned.

95 Upon the shaft of the driving motor 28 (or in modifications upon a shaft geared thereto) is a laminated toothed rotor of ferro-magnetic material 26 of the phonic wheel type, adapted to co-operate with a stator or fixed field winding of any type known in the art. The number of teeth upon the rotor corresponds to and is in a preferred modification of this invention, equal to the number of apertures in one series of apertures in the disc 2: the numbers of apertures 100 in inner and outer series in the disc are, of course, equal. It is preferable to pass a polarization current through the stator winding of the phonic wheel and this may conveniently be the steady plate current of the output valve in the 115 amplifier 24.

110 In operation, according to the present invention the system functions in the following manner.

120 The disc at each of the co-operating stations is rotated at a speed of about 750 revolutions per minute, and the optical systems, including the arc 4, the condensing lens 6 and the projecting lens 10 and their corresponding equivalents at the other station, are adjusted to yield a scanning beam in which the flux of radiation is as large as possible. In the case of luminous radiation, the flux should be at least one third of a lumen, and preferably as high as two or 125 three lumens.

130 Energy diffused from the surface of the operator 8 becomes incident upon the photo cell or photo cells 12, and is there operative in producing an electric signal representing the optical density of each part of the scanned area in turn. 135 This signal, hereinafter referred to as the "first image signal", is passed by way of a suitable thermionic amplifier 14 to a channel of communication 16, which may comprise a pair of wires, a radio link, a submarine cable, or any other 140 suitable transfer means. At the other terminal of this channel is the co-operating station of the two way system, comprising elements respectively the same as and similarly positioned to, those at the station above described. From 145 this co-operating station proceeds a signal (hereinafter referred to as "the second image signal") of type similar to that derived at the station described above.

150 Now the mask or shield 29 is so designed that

light can become operative in scanning the operator only for those periods during which an aperture is within a prescribed portion of its ambit, which portion corresponds to half the 5 distance between successive apertures of the inner series. That is, light is allowed to pass to the scanned area while an aperture is passing across the area 36 shown in Figure 2.

It will thus be seen that two signals are superimposed upon each other in the channel 16, and it is arranged in accordance with this invention that the effect of the superimposed signals (that is, the locally-derived and incoming signals) is vectorially additive. The nature of this condition may best be explained with reference to the curves shown in Figure 5.

Let the curve shown at *a* represent the first image signal, and that at *b* the second image signal, each taken over two complete scanning 20 strips and two intervals.

Let the curve *a*, of which abscissae measure time and ordinates amplitude, be taken as a curve of delivery from the output of the amplifier 14, and curve *b* be taken as a curve of arrival 25 at the same point of signals from the distant station. Then it will be appreciated from the curves that the curve of arrival represents the production of potential differences of the same sign as that of the potential difference generated by the local signals. Suppose that exactly the same number of signals, each representing a strip of the scan, is received from the distant station as is generated locally during each second: then by adjustment of the phase 30 of the local signals it is clearly possible to arrange for the incoming signals just to fill in, as it were, the "troughs" between the potential impulses due to the locally derived signals.

This means, in accordance with the terminology at present current in the art, that the strip-frequency fundamental of the incoming television signals is exactly 180° out of phase with that of the strip frequency of the locally derived signals: If, in addition, it is arranged by 45 suitably balanced amplification, that the amplitudes of the two components thus superposed 180° out of phase are substantially equal, we have the condition illustrated by the dotted 50 curve of Figure 5c, in which the resultant of the two superposed strip-frequency fundamentals is shown to be a straight line—that is, a sensibly constant potential difference,—substantially coincident with the datum line—that is, of sensibly zero value.

These superposed signals are passed by the thermionic amplifier 18 to the neon tube 20, and also, by a branch circuit in shunt, to a 55 circuit 24, which comprises a thermionic amplifier, preferably incorporating a circuit or circuits tuned approximately to the frequency of that component of the television signals which is numerically equal to the number of strips scanned at each station per second. It is, of course, impossible to obtain sharp tuning at such 60 a low frequency because of the inherent resistance of the inductances employed, but this is an advantage, provided that the filtering action of the tuned circuits is adequate to elide components due to details of the configuration in 65 the pictures transmitted. This circuit 24 yields 70 alternating current power to the field circuit associated with the toothed rotor 26, which, it will be remembered, is provided with the same number of teeth as there are apertures in one 75 of the spiral series of the disc 2, and therefore

maintains a fixed phase relationship with the locally generated strip frequency component or with the corresponding component of the incoming signals. This phase relationship may be reckoned as existing between the locally derived signals and the back electromotive force due to the rotation of the rotor near the pole pieces of the stator, and its value is such that maximum current occurs in the field coils, due to the local signals, when the pole-tips of the field are midway between teeth of the rotor. In operation, therefore, since the strip-frequency components of the two sets of signals mutually annul one another, no controlling torque is exerted by the toothed rotor 26 upon the shaft of the motor 28.

If, however, we now relax our hypothetical condition that the incoming signals exactly fit into the "troughs" of the locally derived ones, as it were, then one set of signals will tend to overtake the other in phase, according to which of the two scanning devices is running faster. This state of affairs is illustrated in Figure 5d, wherein the two sinusoidal components of Figure 5c are shown with a phase relationship differing from 180°. A resultant component is generated of phase midway between those of the two signal components, and of amplitude dependent upon the degree of departure from the 180° phase difference hereinbefore postulated. 100 This resultant component rises in magnitude with increasing departure from the 180° phase difference condition (or what amounts to the same thing, with increasing proximity in phase) 105 on the part of the two strip frequency components. By means of the selective amplifier 24 this resultant is passed to the field windings of the toothed rotor 26 and there serves to control its speed and tends to bring the speed of 110 the motor 28 to such a value that the 180° phase difference between the incoming and locally derived components is restored and maintained. This speed-controlling effect on the part of the toothed wheel, fed by the resultant above referred to may be simply explained as follows:— 115

In the normal, or correctly phased, position as previously explained the current maxima (corresponding of course to potential maxima of magnetic intensity in the stator pole pieces, associated with the toothed rotor) due to the locally derived signal, would occur when the stator pole-tips are mid-way between two rotor-teeth if they were not annulled. If, however, the local rotor tends to overspeed, the incoming signals lag on the local ones and a resultant current is 120 applied to the field coils which tends to diminish the magnetization of the field just as a tooth of the rotor is approaching a stator pole-tip, and which increases the magnetization above the normal (which may be assumed to be due to 125 an applied direct current component in the field windings) soon after a rotor-tooth has passed a stator pole-tip. This state of affairs corresponds to the application of a retarding torque to the local rotor, and tends to restore 130 an isochronous running condition between the 135 motors at the two stations.

The same argument may be applied mutatis mutandis to a tendency either to under or overspeed at either station.

As an alternative to the phonic wheel synchronizer 26, I may use a plane metal disc mounted on the motor shaft and rotating in a magnetic field created by the synchronizing impulses after they have been rectified; otherwise 150

the motor 28, may have an extra field winding that is supplied with the rectified synchronizing impulses for the purpose of altering the field and hence the speed of the motor.

5 An exactly similar apparatus is used at the distant station shown at the right hand side of Figure 1.

It will be noticed that whenever an operator is scanned he cannot see the lamp 20 at his own station so that, although his own image signal modulates his own lamp, he will not see his own image. Nevertheless his own image may be revealed to him for monitoring purposes by enlarging the aperture, through which the lamp 15 20 is viewed, in the direction of scanning.

Now the two scanning discs are running at the same speed and with a phase relationship such that when a spot of light is exploring the top strip of an operator's image the disc 20 at the other station is exposing to view the top strip of the glowing plate of the light valve 20.

Figure 2 shows the form of scanning disc used. This has two sets 30 and 32, of spirally arranged apertures so arranged that when an aperture of one set is in either of the areas 34 or 36 (these areas represent the apertures in the mask 29) an aperture in the other set is not within the other area. At the same time 30 it is arranged that an aperture is always within one of the areas. With this type of disc it is clear that single strips of the two operators' images are transmitted alternately but the present invention is not limited to this extent, for example, a plurality of strips of each operator's image may be transmitted alternately or even a complete image or series of complete images may be alternately transmitted provided always that the speed of scanning is such that 40 the reconstituted image appears continuous owing to the retentivity of vision.

Figure 3 shows the phase relationship that has to be maintained between the two scanning discs. In this figure the apertures 38, 40 and 42, are on the disc at (say) the near station and the apertures (shaded in the drawings, in order to distinguish them) 44, 46 and 48, are on the disc at the far station. It will be seen that the corresponding apertures 40 and 50 46 occupy similar positions in their respective areas 34 and 36. The effect produced by a departure from this phase relationship is illustrated in Figure 4; in this diagram the far disc is shown in advance of the near disc so that when the aperture 40 comes into the area 34 the aperture 46 will already be a certain distance in the area 36 and when the aperture 46 goes out of the area 36, the aperture 40 will still be a distance in the area 34. The result is that 55 the image of the operator at the far station will be displaced to the left of the area 34 on the near station disc, and a black band will appear at the other edge of the picture, while at the far station the image of the near operator will be displaced to the right of the area 34 and a black band will appear at the left side of the area 34. If the discs get sufficiently out of phase the image of the far operator will pass, 60 towards the left-hand side, right out of the area 34 at the near station leaving a blank space while the image of the near operator will pass right out of the area 34 at the far station by way of the right-hand side.

The image signals are applied to the line 50, by means of the transformers 52 and 53, at the

near and far stations respectively. The input terminals of the valves 54 and 56 situated at the near and far stations respectively, are also connected across the line 5. The grid electrodes of these valves being so biased that the valve 54, is working on the bottom bend of its characteristic while the valve 56, is working on the top bend of its characteristic.

The anode circuits of these valves each contain a transformer that feeds the corresponding neon-glow lamp amplifier. Now, the image signal impulses are put on to the line in such a sense that those from the near station cause the upper conductor shown in the figure (and consequently the grids of the two valves 54 and 56) to become negatively charged relative to the lower conductor and the valve filaments. The result is that the impulses create corresponding impulses in the anode circuit of the distant valve 56, but have no effect on the anode current of the near valve 54, since the grid is already negatively biased so that the valve is at the bottom bend of its characteristic. Alternatively a commutator, arranged upon the shaft of the motor driving the scanning device, 100 may disconnect the local glow lamp amplifier when the local image signals are on the communicating line.

It will be appreciated that it is desirable, in the case of spotlight scanning, to cut out the 105 visible components of the scanning beam and to pass only the ultra-violet or infra-red radiations extant in the light, in order that the observer at each station may, without embarrassment or dazzle, view the image reconstituted before him. 110 This may be accomplished by interposing a suitable filter in the path of the light, for instance, between the disc and scanning lens.

In the specification of British Letters Patent No. 288,882 is described means whereby a person sitting in darkness may be viewed by an apparatus using invisible rays, this apparatus consisting of an exploring and a viewing device mounted upon the same rotating member. This particular device is eminently suitable for 120 two-way television, one of each of these devices being placed at the sending and receiving station and rotated synchronously.

In connection with all the arrangements hereinbefore described, it will be appreciated by those skilled in the art, that appropriate measures must be taken in order to ensure that with any particular arrangement the reconstituted image of the object at the distant station portrays that object not only the right way up, but 130 also without lateral inversion. This end is usually accomplished in any given case by appropriately choosing the direction of throw of corresponding transmitting and receiving spirals, or by inserting an inverting lens or prism 135 or pair of mirrors in some appropriate position in the path of the scanning or image-forming rays, or in cases where two geared or otherwise coupled mechanisms are used, one for scanning and the other for reconstituting, the sense of rotation must be fixed by consideration of the system as a whole.

It should be noted also that either vertical or horizontal strip-scanning may be employed, though in a preferred embodiment according to 145 the present invention, I purpose to employ horizontal scanning in order that when a single disc provided with two concentric spirals is employed at each station, using the method of exploration technically known as "spotlight" scan- 150

ning, in which a scanning or projection lens is interposed in the path of the scanning rays, the image reconstituted at the receiver by means of a flat-plate neon tube behind the disc may 5 be reproduced the right way up by choosing the throw of the receiving spiral in the opposite sense to that of the transmitting spiral, so that lateral inversion is obviated. This is clear on detailed consideration of the system, for sup- 10 pose the observers see the scanning apertures moving from right to left, then, owing to the scanning or projection lens above mentioned, the scanning light spots move from left to right; thus lateral inversion does not exist, since the 15 neon plates are also exposed from their left to their right sides. It is, of course, necessary to choose the throw of the transmitting and receiving spirals in the opposite sense, so that if the receiving apertures move from top to bottom 20 of the image, the transmitting apertures must move up, so that, owing to the projection lens, the scanning light spot moves down, that is from top to bottom of the object.

It will be obvious to any person skilled in 25 the art than any other convenient form of scanning or reconstituting device might be employed in place of discs with spirally arranged light-transmitting devices.

For instance, in another embodiment accord- 30 ing to the present invention, we may employ two mirror-drums driven by the same motor, one for scanning the object and the other for recon- stituting an image, at each station. Obviously, 35 the same method of synchronizing and of later- ally shifting the scanning beam on to the ob- server's face while he is looking at the recon- stituted image is applicable.

I may also employ apertured or lensed drums 40 or truncated cones for scanning and for recon- stitution.

In alternative modifications, it may be more 45 convenient to employ floodlighting instead of spotlighting for scanning the object at each station.

An additional advantage of the system of two- 50 way television, hereinbefore described, is that when a single disc is employed with two spirals of apertures, by appropriate arrangement of the

mask usually employed to limit or frame the received picture—for instance, by enlarging its dimension in the direction of rotation of the disc to double that value which is required to expose only the picture received from the opposite sta- 80 tion—a picture of the observer's own person may be presented to him, side by side (in the case of horizontal scanning) with that of the distant observer.

Having described my invention, what I claim 85 as new and desire to secure by Letters Patent is:—

1. In or for a two-way television system means for maintaining syntony between the scanning mechanisms at the two stations comprising a scanning disc at each station having apertures arranged to give intermittent scanning and a phonic wheel at each station controlling the rotation of the said scanning discs and fed with the combined signals generated by the said discs. 90

2. In or for a two-way television system means for maintaining syntony between the scanning mechanisms at the two stations comprising a scanning disc at each station having apertures arranged to give interrupted scanning and a phonic wheel at each station controlling the rotation of the said scanning discs and fed with a polarizing direct current upon which is superimposed the combined signals generated by scanning with the said discs. 95

3. A duplex television system consisting in two stations connected by a single channel each station comprising a light valve, a light sensitive cell and a synchronizing device, all connected through amplifiers to the said channel, and a scanning disc, whose motion is controlled by the said synchronizing device, bearing two sets of spirally arranged apertures interdigitated to scan groups of strips of the image of the ob- server and to reconstitute groups of strips of the 110 image of his co-operator alternately; the said light sensitive cell and light valve being con- nected to the channel in such a sense that local signals coming from the light sensitive cell and distant signals going to the light valve are out 115 of phase as regards a principal component of their waveforms. 120
